UNITED STATES PATENT OFFICE.

ANTON C. MENGE AND WILLIAM H. PIPES, OF MYRTLEGROVE, LOUISIANA.

BOILER-FLUE CUTTER.

1,271,345.

Specification of Letters Patent. Patented July 2, 1918.

Application filed February 2, 1917. Serial No. 146,187.

To all whom it may concern:

Be it known that we, ANTON C. MENGE and WILLIAM H. PIPES, citizens of the United States, residing at Myrtlegrove, in 5 the parish of Plaquemine and State of Louisiana, have invented new and useful Improvements in Boiler-Flue Cutters, of which the following is a specification.

This invention relates to boiler flue cutters 10 and it consists in the novel features herein-after described and claimed.

An object of the invention is to provide a cutter of simple and durable structural arrangement adapted to be used for cutting 15 a flue at a desired predetermined distance from the crown sheet of a boiler, and with this object in view the device includes a tube having openings at its sides and arms adjustably mounted in the tube and provided 20 with cutting disks which project through said openings. A wedge-shaped block is movably mounted in the tube and may be used for spreading the arms with relation to each other whereby the said disks 25 will be projected through the openings in the tube to the desired extent. A flanged collar is mounted upon the tube and may be shifted longitudinally thereof by means of plates which are adjustably mounted on said tube. 30 A band is attached to the tube and provided with ratchet teeth and the ring of a wrench surrounds the said band and the teeth thereof and a spring pressed pawl which is carried by the wrench is adapted to engage the 35 teeth of the band whereby the same together with the tube is turned.

In the accompanying drawing:—

Figure 1 is a top plan view of the boiler flue cutter.

40 Fig. 2 is a longitudinal sectional view of the same taken on the line 2—2 of Fig. 1.

Fig. 3 is a similar view taken on the line 3—3 of Fig. 2.

Fig. 4 is a transverse sectional view of 45 the same taken on the line 4—4 of Fig. 1.

Fig. 5 is a similar view taken on the line 5—5 of Fig. 2.

The boiler flue cutter comprises a tube 1 which is provided at its sides with openings 2. Arms 3 are movably mounted in the tube 1. The arms 3 are provided at their inner sides with wear plates 5 which bear against the surfaces of a wedged block 6 slidably mounted in the tube 1. The said block 6 is provided at a point between its edge with

a longitudinally disposed slot 7 which receives a bolt 8, the said bolt in turn being secured at its ends to the opposite sides of the tube 1 and disposed transversely thereof. The said slot 7 together with the bolt 60 8 serve as means for limiting the sliding movement of the wedge block 6. Springs 9 are interposed between the inner surface of the arms 3 and are under tension with a tendency to hold the wear plates 5 against 65 the adjacent surfaces of the wedge block 6. Cutting disks 10 are carried by the arms 3 and located in the openings 2 of the tube 1. The said springs 9 also serve as means for holding the disks 10 at inner positions in 70 the openings 2 as best indicated in Fig. 2 of the drawing. A collar 11 snugly receives the tube 1 and the said collar is provided at its end with an annular outstanding flange 12. Plates 13 are mounted upon the end 75 portions of the bolt 8 and secured at adjusted positions by means of nuts 14 screw-threaded upon the said bolt and which serve in conjunction with bars 15 as means for holding the plates at adjusted positions 80 upon the bolt 8 and against the flange 12 of the collar 11. The plates 13 are provided with longitudinally disposed slots 16 which receive the bolt 8, consequently when the nuts 14 are loosened the plates 13 may be 85 moved upon the bolt 8 and inasmuch as the said plates bear against the said flange, the said flange 12 may be moved away from the bolt 8 or adjusted with relation to the same. When the flange 12 is at position 90 with relation to the bolt 8, the nuts 14 are tightened whereby the said flange 12 and the collar 11 are secured at an adjusted position.

A band 17 is screwthreaded upon the outer end of the tube 1 and is provided around its periphery with a set of ratchet teeth 18. A ring 19 is rotatably mounted upon the band 17 and carries a spring pressed pawl 20 which engages the teeth 18. The said ring 19 is further provided with a handle 21. A yoke 22 is attached to the band 17 and a bolt 23 is screwthreaded through the intermediate portion of the said yoke 22 and at its inner end engages the 100 block 6. A hand wheel 24 is mounted upon the bolt 23 and may be used for turning the same. Arms 25 are secured at their ends to the tube 1 by means of screws 26 best shown in Fig. 3 of the drawing and the said arms 110

carry at their opposite ends rollers 27 which are located in openings 28 provided at the sides of the tube 1.

Wedges 30 are interposed between the inner edges of the arms 25 and partitions 31 which serve as guides for the wedge block 6. Screws 32 are threaded through the yoke 22 and their inner ends are journaled in cores 33 which are screwthreaded upon the wedges 30. Handles 34 are carried at the outer ends of the screws and may be used for turning the same.

The nuts 14 upon the bolt 8 are loosened and then the plates 13 are moved whereby the collar 11 and the flange 12 are moved longitudinally along the tube 1. This adjustment is desirable in order to position a flange 12 at a desired distance from the cutting disks 10. The end portion of the tube 1 which carries the cutting disks 10 is then inserted in the boiler flue so that the flange 12 is brought against the end of the flue as indicated in dotted lines in Fig. 1 of the drawing. By using the hand wheel 24 the bolt 23 is moved longitudinally through the yoke 22 and consequently the wedge shaped block 6 is moved longitudinally and the arms 3 are spread with relation to each other whereby the outer portions of the peripheries of the disks are moved beyond the outer surface of the tube 1 and into contact with the inner surface of the boiler flue. An operator may then use the handle 21 as a lever whereby through the engagement of the spring-pressed pawl 20 and the teeth 18 and the band 17 the tube 1 is rotated. Thus the cutting disks 10 are carried around in a line at the inner surface of the boiler flue and by continuing the operation just described the said flue is cut at a desired distance from the crown sheet of the boiler. During the turning movement of the tube 1 in the boiler flue the outer portions of the peripheries of the rollers 27 travel along the inner surface of the flue and they serve as means for preventing the cutting disks from entering too deeply into the boiler flue and thus wedging the device and interfering with the prompt cutting operation of the same.

Copies of this patent may be obtained for five cents each, by addressing the "Commissioner of Patents, Washington, D. C."

By loosening the screws 26 the wedges 30 may be moved longitudinally by turning the screw bolts 32 and thus the rollers 27 may be projected more or less through the openings 28 and when they are at desired positions in the said openings they may be secured by tightening the screws 26 against the wedges 30.

From the foregoing description taken in conjunction with the illustration, it will be seen that a boiler flue cutter of simple and durable structural arrangement is provided and that the same may be economically and conveniently used for efficiently and effectively cutting a boiler flue at a desired distance beyond the crown sheet of the boiler.

Having described the invention what is claimed is:

1. A boiler flue cutter comprising a tube provided with openings, arms located in the tube, springs interposed between the arms and tube, a wedge-shaped member interposed between the arms, means for moving the wedge-shaped member longitudinally, cutting disks carried by the arms and located in the openings of the tube, collar mounted upon the tube and having an outstanding flange, plates mounted upon the tube and engageable with the flange to move the collar with relation to the tube and means for rotating the tube.

2. A boiler flue cutter comprising a tube provided with openings, arms located in the tube, springs interposed between the arms and tube, cutters carried by the arms and located in the openings of the tube, a wedge-shaped block interposed between the arms and means for moving the block, a collar adjustably mounted upon the tube, means for moving the collar, a band attached to the tube having ratchet teeth and a ring journaled on the band, and having a spring-pressed pawl which engages the teeth and adapted to be used as means for rotating the tube.

In testimony whereof we affix our signatures.

ANTON C. MENGE.
WILLIAM H. PIPES.
